C. U. GILSON.

SIGNATURE MARKING MEANS FOR PAPER FOLDING MACHINES.

APPLICATION FILED FEB. 5, 1915.

1,212,623.

Patented Jan. 16, 1917.

UNITED STATES PATENT OFFICE.

CLAUDE U. GILSON, OF WELLESLEY, MASSACHUSETTS.

SIGNATURE-MARKING MEANS FOR PAPER-FOLDING MACHINES.

1,212,623.

Specification of Letters Patent. Patented Jan. 16, 1917.

Application filed February 5, 1915. Serial No. 6,260.

To all whom it may concern:

Be it known that I, CLAUDE U. GILSON, a citizen of the United States, and resident of Wellesley, in the county of Norfolk and State of Massachusetts, have invented certain new and useful Improvements in Signature-Marking Means for Paper-Folding Machines, of which the following is a specification.

This invention is embodied in a marking attachment for a flat support on which the backs of, or back edges of, book and pamphlet signatures delivered by a folding machine are in sliding contact, the signatures being moved sidewise on the support. Preferably the back support is one of the inclined sides or members of an angular trough such as is commonly used with paper folding machines, the other inclined side or member of the trough constituting an auxiliary support and a guide which maintains the signatures with their ends in alinement while their backs are passing over the back support, the said auxiliary support sustaining a portion of the weight of the signatures. The back support may however be a horizontal table supporting the entire weight of the signatures, suitable guiding means being provided for keeping the ends of the signatures in alinement with each other while their backs or back edges are moving on the support.

In the following description I refer to the signatures bearing the same printed matter as a set or lot of identical signatures, and to the serially numbered signatures which are subsequently collated to form a publication, as a series of signatures.

This invention is embodied in an attachment for a signature-back-support whereby the back edges of the signatures are marked while they are moving on the support, a marker being employed which is adapted to be located at various predetermined distances from an edge of the support and from the ends of the signatures and form coinciding marks on the backs of each set or lot of identical signatures accumulated and moved on the support. When the signatures of one set have been marked, the marker is adjusted at a different distance from the ends of the signatures, so that the signatures of the next set are provided with marks distinguished by their location from the marks of the first set, and so on until each set of identical signatures has been

marked. The marks guide the operator in serially collating the signatures, each member of the series bearing a mark differing in location from the marks on the other members, so that the marks conspicuously indicate the seriality or order in which said members should be assembled, all as herein-after described.

Of the accompanying drawings forming a part of this specification, Figure 1 represents a transverse section of the angular trough of a paper folding machine provided with an attachment embodying my invention, said attachment being shown in elevation; Fig. 2 represents a section on line 2-2 of Fig. 1, and a side view of the parts at the right of said line; Fig. 3 represents a section on line 3-3 of Fig. 2; Fig. 4 represents a section on line 4-4 of Fig. 3; Fig. 5 represents an end view of the attachment separated from the trough. Fig. 6 represents in perspective parts of a series of four signatures collated by the marks thereon; Fig. 7 represents a sectional view illustrating modifications.

The same reference characters indicate the same or similar parts in all the views.

In the drawings, representing the preferred embodiment of my invention, 12 represents the signature-back-sustaining member of an angular trough such as is commonly employed to receive folded signatures from a folding machine, and 13 represents the complementary signature-end-retaining member of the trough, the angle or inverted apex formed by the intersection of said members being shown at 14.

The back-supporting member 12 is preferably inclined, as shown by Fig. 1, so that signatures deposited edgewise thereon will be moved by gravitation until their inner ends contact with the end-supporting member 13, said inner ends being therefore automatically rendered flush or brought into alinement with each other before the backs are marked.

With the member 12 is associated a marker 16 which is adapted to project slightly above the upper surface of said member and contact with and mark the folded inner or back edges of signatures deposited and moved in the trough, the marker being movable toward and from the apex 14 and adapted to be located at various predetermined distances from said apex, so that the members of a set of identical signatures moving in

the trough may be marked at a given distance from their lower ends, and the members of the next set may be marked at a different distance from their lower ends, the 5 marker being re-located after each set is marked. As here shown, the marker 16 is annular and composed of a ring of rubber the periphery of which projects slightly above the upper surface of the trough member 12, and is in rolling contact with the 10 back edges of the signatures moved along the trough, the said periphery being supplied with ink or coloring matter by an inking roll 17. The annular marker is supported by a flanged wheel body or hub 16^a. I do not limit myself however to a rotary 15 marker, nor to the means hereinafter described for supporting and adjusting or locating the same.

20 I have here illustrated marker supporting and adjusting or locating means adapted particularly to support and adjust a rotary marker, said means including a marker guide 18 and a marker carrier or bearing 19 which is slidable on said guide, and on which the marker 16 is adapted to rotate loosely. I have also illustrated means for retaining the marker in any one of a plurality of predetermined positions. In view of the necessity 25 of frequently changing the position of the marker, I have so organized said retaining means as to permit a quick release and a quick confinement of the marker, so that the time required to adjust it from one position 30 to another is reduced to the minimum.

The member 12 is provided with a transverse opening 15 (Fig. 1) extending from a point near the upper edge of said member to a point at or near the apex 14. The 40 marker guide 18 extends from end to end of said opening and somewhat below the same, and is substantially at right angles with the apex of the trough. Said guide is a rod rigidly attached at its ends to supports 45 20 which are preferably slides movable in fixed guide frames 21 projecting from the under side of the trough member 12. The marker hub 16^a is loosely rotatable on the bearing 19 and confined between collars 19^a 50 attached to the bearing. The guide 18 is square in cross section and the central aperture of the bearing 19 is correspondingly formed, as shown by Fig. 4, so that the bearing slides but does not rotate on the guide. 55 The guide 18 and bearing 19 are or may be provided with complementary means for locating the marker in any one of a series of predetermined positions at different distances from the apex of the trough. As 60 shown by Fig. 3, the guide has a series of sockets 22 spaced equally apart, and the bearing has a spring-pressed stud 23 adapted to enter either of said sockets. The stud and sockets yieldingly engage the bearing with 65 the guide, indicate by their interengage-

ment the fact that the bearing has been moved to a predetermined point on the guide, and prevent loose or accidental movement of the bearing from said point, the stud yielding when sufficient pressure is exerted on the 70 bearing to move it endwise.

In the preferred embodiment of the invention the marker is yieldingly supported in its operative position, so that it is adapted to bear yieldingly on the signature backs, 75 the yielding supporting means being preferably organized to permit the marker to be entirely withdrawn from the opening 15, as indicated by dotted lines in Fig. 4. To this end the guide supports 20 are formed 80 as slides supported by springs 23^a surrounding rods 24 attached to the slides 20, and movable through the lower ends of the guide frames 21. Said springs bear on the lower 85 ends of the guide frames and on the slides 20 and yieldingly support said slides, the marker guide, and the marker with the highest part of the periphery of the marker slightly above the upper surface of the trough member 12, and projecting into confining slots formed by fixed uniformly spaced bars 27 extending across the opening 15. Said bars are preferably integral parts 90 of a plate 27^a, which is attached at 28 to fixed frame bars 29, the latter being attached at 31 to the trough member 12. Said bars 29 and transverse bars 32 attached at 32^a to the ends thereof constitute a supporting 95 frame which supports the guide frames 21.

The transverse bars 27 constitute marker 100 locating means which may be used either with or independently of the sockets 22 and stud 23 above described, the spacing of the bars corresponding to that of the sockets so that the bars constitute stops to prevent 105 lateral movement of the marker on its guide 18 when the marker projects operatively between two of the bars 27. The bars or the slots between them may be serially designated by numerals inscribed on the plate 27^a, 110 as shown by Fig. 2.

It will now be seen that the marker may be located in either of a series of predetermined positions at different distances from the apex of the trough by shifting it from 115 slot to slot, the marker being depressed as shown by dotted lines (Fig. 4) to withdraw it from a slot, moved laterally to another slot, and released and allowed to spring upwardly into the last mentioned slot.

The marker may be depressed by means provided for that purpose and including levers 30 pivoted at 30^a to the guide frames 21, and connected by links 33 with the slides 20, said levers being connected by a cross bar 30^b whereby they are simultaneously depressed.

The inking wheel 17 is journaled in the swinging ends of arms 34 pivoted on a rod 35 which is attached to the lower ends of 130

120

125

5 downwardly projecting arms 36 attached to the sliding bearing 19. A spring 37 connecting the swinging arms 34 with the bearing arms 36 holds the inking wheel in yielding contact with the marker.

10 By reference to Fig. 6 it will be seen that a series of collated signatures 38 will show on their backs a series of marks 39 made by the marker, said marks forming an oblique row across the back of the bunch of collated signatures. The lowest mark is formed on all the members of an identical set of signatures when the marker is at the minimum distance from the apex of the trough. The 15 next mark above is formed on all the members of another identical set of signatures when the marker has been located in its next position farther from the apex, and so on. The operator who collates the signatures is 20 therefore enabled to determine by a glance at the marks whether the signatures have been properly collated or not.

25 It will be understood that the usual or any suitable means will be employed to move the signatures progressively in the trough, and cause their backs to pass over the marker.

30 As already stated, the support for the signature backs may be horizontal instead of being inclined. Fig. 7 shows a horizontal signature-back support or table 12^a having at one edge a guide 13^a adapted to keep the ends of the signatures in alinement with each other. The plate carrying the spaced bars 27 is designated 27^b in this figure, and is hinged to the table at 27^c, so that it may be raised as indicated by dotted lines to release the marker 16. In this modification the marker guide 18 is 35 attached to fixed ears 20^a substituted for the slides 20, and when the marker is to be adjusted, the plate 27^b is raised, the marker is moved laterally, and the plate 27^b is lowered to confine the marker in its adjusted position.

40 In case the marker is movable toward and from the support as in the first described embodiment of the invention the spaced bars 27 may be integral with the support 50 and formed by cutting slots therein to interrupt its continuity.

45 Each embodiment of my invention above described includes a support such as the table 12, 12^a, for supporting a group of signatures, the backs of which rest on the support, a signature guide such as the member 13 or 13^a engaging one end of the group of signatures and guiding the group in a predetermined path on said support, a 55 marker adapted to mark the backs of the signatures moving in said path, marker supporting means, such as the marker guide 18 and its supports, a marker carrier, such as the bearing 19, slidably engaged with the 60 guide, said guide and carrier permitting the 65

adjustment of the marker in a path transverse to the signature guide and to the path of the signatures, and positioning means including a series of stop members mounted on the support and confined against movement in the path of the marker, a complementary stop member movable with the marker, and means for yieldingly holding said complementary stop member in engagement with either of the series of stop members on the support, the arrangement being such that the marker may be quickly released from confinement, moved to another position, and automatically confined in the last position.

70 The series of stop members confined on the support against movement in the path of the marker may be embodied in the walls of the slots in the plate 27^a, or in the sockets 22. The complementary stop member movable 75 with the marker may be embodied in the hub 16^a coöperating with said slot walls, or in the stud 23 coöperating with the sockets 22 in the bar 18. The means for holding the said complementary stop member in 80 yielding engagement with either of the series of confined stop members may include the springs 23^a supporting the slides 20 and rod 18, or the spring which projects the 85 stud 23.

90 As implied in the foregoing description and in the following claims, I am not limited to the specific mechanism of the preferred embodiment of my improvements shown by the drawings except as otherwise 95 required in certain of the more limited claims.

100 Having described my invention, I claim:

1. In a device of the character stated, in combination, a back-supporting member and an end-supporting member collectively forming a two-sided signature guiding support, said back-supporting member being inclined to cause an endwise movement, by gravitation, of signatures deposited endwise thereon and bring the inner ends of said signatures against said end-supporting member and thus cause the automatic alinement of the signatures, and a marking member arranged to mark signature backs 110 guided by said support.

115 2. In a device of the character stated, in combination, a back-supporting member and an end-supporting member collectively forming a two-sided signature-guiding support, said back-supporting member being inclined to cause an endwise movement, by gravitation, of signatures deposited edgewise thereon and bring the inner ends of said signatures against said end-supporting 120 member and thus cause the automatic alinement of the signatures, a marking member arranged to mark signature backs guided by said support, one of the parts called respectively the back-supporting member and 125 130

- the marking member being movable relatively to the other, to vary the distance between the marks and the inner ends of the signatures, and means for retaining said movable member in any one of a plurality of predetermined positions.
3. In a device of the character stated, in combination, a back-supporting member and an end-supporting member collectively forming a two-sided signature-guiding support, said back-supporting member being inclined to cause an endwise movement, by gravitation, of signatures deposited edge-wise thereon and bring the inner ends of said signatures against said end-supporting member and thus cause the automatic alinement of the signatures, a marking member arranged to mark signature backs guided by said support, the marking member being movable relatively to the end-supporting member to vary the distance between the marks and the inner ends of the signatures, and means for retaining the marking member in any one of a plurality of predetermined positions.
4. In combination, a signature-back-support, a signature guide adapted to direct a group of signatures in a predetermined path on said support, a marker adapted to mark the backs of signatures moving in said path, marker-supporting means permitting the adjustment of said marker in a path transverse to the path of the signatures, and positioning means for selectively confining said marker in either of a series of predetermined positions at different distances from said guide, said positioning means including a series of stop members confined against movement in the path of the marker, and a complementary stop member movable with the marker and arranged to coact with a member of said marker-supporting means for yieldingly holding said marker in predetermined positions.
5. In combination, a signature-back-support having a series of marker-receiving and confining slots interrupting its continuity, said slots being at different distances from said guide, a marker adapted to enter either of said slots, and marker-supporting means adapted to support the marker in separable engagement with either of the slots.
6. The combination with a signature-back-support having a transverse opening, of a marker, marker-supporting and guiding means having provisions for yieldingly holding the marker above the upper surface of said support and for guiding the marker to different parts of said opening, and spaced bars extending across said opening and forming a series of marker-receiving and confining slots.
7. The combination with a signature-back-support having a transverse opening, of a marker guide extending lengthwise of said opening, yielding means normally supporting the guide in operative relation to said support and permitting lateral movement of the guide from the support, a marker supported by and movable upon said guide and normally held thereby above the upper surface of the support, and spaced bars extending across said opening and forming a series of marker-receiving and confining slots located at different distances from an edge of the support.
8. The combination with a signature-back-support having a transverse opening, of fixed guiding frames projecting downwardly from said support at opposite ends of said opening, slides movable in said frames and yieldingly pressed toward the support, a marker guide secured to said slides and extending lengthwise of said opening, a marker supported by and movable upon said guide and normally held yieldingly thereby above the upper surface of said support, and spaced bars extending across said opening and forming a series of marker-receiving and confining slots located at different distances from an edge of the support, the said marker guide and slides being depressible to permit the transference of the marker from slot to slot.
9. The combination with a signature-back-support having a transverse opening, of fixed guiding frames projecting downwardly from said support at opposite ends of said opening, slides movable in said frames and yieldingly pressed toward said support, a marker guide secured to said slides and extending lengthwise of said opening, a marker supported by and movable upon said guide and normally held yieldingly thereby above the upper surface of said support, spaced bars extending across said opening and forming a series of marker-receiving and confining slots located at different distances from an edge of the support, the said marker guide and slides being depressible to permit the transference of the marker from slot to slot, and means for depressing said marker guide and slides.
10. The combination with a signature-back-support having a transverse opening, of fixed guiding frames projecting downwardly from said support at opposite ends of said opening, slides movable in said frames and yieldingly pressed toward said support, a marker guide secured to said slides and extending lengthwise of said opening, a marker supported by and movable upon said guide and normally held yieldingly thereby above the upper surface of said support, spaced bars extending across said opening and forming a series of marker-receiving and confining slots located at different distances from an edge of the support, the said marker guide and slides being

depressible to permit the transference of the marker from slot to slot, levers pivoted to said guiding frames, and connected with each other by a cross-bar, and links connecting said levers with the slides, whereby the slides and marker guide may be depressed.

11. The combination with a signature-back-support having a transverse opening, of a marker guide extending lengthwise of said opening, means for supporting said guide, a bearing mounted to slide without rotation on said guide, a marker formed as a wheel loosely rotatable on said bearing, means for locating said bearing and marker on different portions of said guide, and means carried by said bearing for inking the periphery of the marker.

12. The combination with a signature-back-support having a transverse opening, of a marker guide extending lengthwise of

said opening, means for supporting said guide, a bearing mounted to slide without rotation on said guide, a marker formed as a wheel loosely rotatable on said bearing, 25 means for locating said bearing and marker on different portions of said guide and at different distances from an edge of the support, spaced-apart arms attached to said bearing and projecting downwardly therefrom, a swinging spring-pressed carrier 30 pivoted to said frame, and an inking wheel journaled on said carrier and pressed thereby against the periphery of the marker.

In testimony whereof I have affixed my signature, in presence of two witnesses.
